UNITED STATES PATENT OFFICE

MARION F. MITAR, OF OAKLAND, CALIFORNIA

PANTS-LEG STRETCHER

Application filed May 31, 1930. Serial No. 457,732.

The invention relates to a pants-leg stretcher by which creases are produced and maintained.

An object of the invention is to provide an improved and simplified stretcher of the type described and wherein adjustment for its best operative fitting to pants legs of various sizes is arranged to be effected with particular readiness.

10. Another object is to provide a stretcher of the class described which is formed of flat and mutually pivoted elements in such manner as to permit a folding of the stretcher into a compact and relatively flat package.

15. A further object of the invention is to bring about a new combination and correlation of parts in a device of the class described whereby marked economies in manufacture will be effected and the efficiency of 20 the device will be enhanced.

Yet another object is to provide a stretcher in which the degree of stretching is least at the cuff end of a pants leg.

The invention possesses other objects and 25 features of advantage, some of which, with the foregoing, will be set forth or be apparent in the following description of a preferred form of the invention which is illustrated in the accompanying drawing, in which:

30. Figure 1 is an elevation of a stretcher embodying the present invention and showing the stretcher as engaged in a pants leg in partially operative relation thereto, a fully operative disposal of the stretcher elements 35 being indicated in dash-and-dot lines.

Figure 2 is an enlarged perspective view of a portion of the stretcher structure.

Figure 3 is an elevation showing the stretcher in collapsed condition.

40. Figure 4 is an enlarged fragmentary section at 4-4 in Figure 1.

Essentially, the present device comprises a pair of flat and laterally spaced bars 5 and 6 arranged for forcible engagement within 45 the opposite creases of a pants leg or the like to produce and/or maintain said creases, and means coactive between said bars to mutually spread them within the pants leg to their operative positions. The bars 5 and 6 are 50 of suitable length and strength, and their

crease-engaging edges may be shaped as desired or required; in the present instance, said bar edges are straight. The elements of the means which controls the relative bar disposal comprise a strut member 7, two each 55 of links 8 and 9, and a pull-rod 11, all said elements being formed of rigid strap metal or other suitable material and being pivotally connected to each other and the bars 5 and 6 in such manner as to provide an operative 60 combination, as hereinafter described.

The strut member 7 is pivotally secured to one end of the bar 6, and lies opposite a face of the bar whereby it may be swung from its operative position of extension toward the 65 bar 5 to a folded position against and along the bar 6; the aforesaid positions of the strut are disclosed in Figures 1 and 3 respectively. A ratchet rack 12 is provided along one edge of the strut member 7 for engagement therewith of a pawl 13 extending transversely from the bar 5 whereby to adjustably space the bars by use of the strut. The bar portions adjacent said strut are arranged to engage the cuff ends of a pants leg with the strut 75 lying outwardly of and along the doubled cuff, as is indicated in Figure 1. It is noted that the ratchet teeth point generally away from the pivoted end of the strut 7 whereby to engage the pawl 13 to hold the bar 5 against 80 movement toward the bar 6. As particularly shown, the pawl 13 is provided as part of an integral portion 14 of the bar 5, said bar portion having an outer part 15 parallelly offset from the bar and an inner connecting part 85 transverse to the bar and providing the pawl 13. Preferably, the ratchet is provided at the inner edge of the strut 7 and the part 15 extends outwardly from the pawl to cooperate with the opposite bar portion to define a 90 guideway for the strut from which the strut may be swung for disengagement from the pawl for collapsing or folding the stretcher.

The links 8, it will now be noted, are pivoted at one end thereof to the bars 5 and 6 adjacent the pawl 13 and the pivot point of the strut 7 respectively, and the other ends of the links 8 are pivotally fixed together by means of a pivot pin 16. When the pawl 13 engages the rack 12, the links 8 are ar- 100

ranged to be angularly related and their common pivot point at the pin 16 is arranged to then lie inwardly of the strut member 7.

The links 9 are mounted and related to each other and the bars 5 and 6 as are the links 8, except that their pivotal connection with the bars 5 and 6 is mediate of said bars. These links are toggle members and are each preferably provided with a plurality of pin-receiving perforations 17 at their connected ends whereby their effective lengths may be adjustably varied. As particularly brought out in Figure 4, a screw 18 pivotally engaged through a perforation 17 of one bar 9 is threadedly engaged in a perforation 17 of the other bar, said screw comprising the pivot pin for the links 9. The inner end of the rod 11 is provided with a series of perforations 19 for the selective reception of the pivot pin 18. As particularly shown, the rod 11 engages the pivot screw 18 between the links 9, and the screw is provided with a shoulder 21 for limiting its degree of engagement in the link 9 which it threadedly engages whereby to provide for the free pivoting of the other bar 9 and the rod 11 on the screw pin 18. The rod 11 is arranged to extend longitudinally of and between the bars 5 and 6 and outwardly beyond the pants cuff whereby it may be engaged for pulling it to increase the angle between the links 9 and so spread said bars, the action being obviously that of a toggle joint. A handle in the form of a hook 22 is provided on the extending rod end for facilitating an operative manipulation of the rod.

Means are provided for securing the rod 11 in a pulled-out relation whereby to maintain the described toggle spread. As particularly shown, the outer end portion of the rod 11 is formed with a ninety degree twist 23, beyond which that rod edge which lies nearest and opposite the strut member 7 is provided with a ratchet rack 24 having its teeth directed inwardly and arranged to receive the outer edge portion of the strut 7. To facilitate this cooperative engagement of the strut 7 and rack 24, the former is preferably formed at its outer edge, and mediate thereof, to provide a transversely oblique lip 25 which is operative as a pawl with respect to the rack.

A major function of the links 8, it will now be noted, is their cooperation with the toggle links 9 to prevent any relative longitudinal shifting of the bars 5 and 6. These links are further utilized for maintaining the rod 11 in the plane of the creaser bars, and to that end the pivot pin 16 which connects them is slidably engaged through a longitudinal slot 26 provided in the rod 11, said rod lying between the links 8 at the pin. The length and disposition of the slot 26 is such that neither slot end engages the pin 16 as the rod 11 is shifted to operate the toggle joint at the links 8, it being noted that the bar 7 and links 8

cooperate to substantially define a triangle at the cuff engaging end of the stretcher structure.

The specific link arrangement with respect to the bars 5 and 6 and the rod 11 is seen to be such as to permit a collapsing of the present stretcher to have the said bars and rod in coplanar and laterally abutting relation, the stretcher being shown in such collapsed condition in Figure 3.

To operably install the now-described device, the stretcher is first placed in a pants leg in more or less collapsed condition and with the cuff-engaging portions of the bars 5 and 6 slightly protruding to permit an operative disposal of the strut 7. With the strut 7 in position for engagement of the pawl 13 with teeth of the strut rack, the bar ends at the cuff are pulled apart by hand whereby to slightly stretch the cuff and operably engage the strut for maintaining the cuff stretched, this being the condition shown in full lines in Figure 1. The rod 11 is now pulled to cause an angular spreading of the bars 5 and 6 through the toggle action of the links 9, whereby the bars are disposed in operative position with any desired degree of stretching of the pants leg, engagement of the strut lip 25 with the rod rack 24 being effected to adjustably secure the rod in its pulled-out and operative position. The final operative disposal of the structure parts is disclosed in dash-and-dot lines in Figure 1.

A peculiar and novel feature of the present device is seen to lie in the angular spreading of the creaser bars 5 and 6 as they move to position whereby the degree of stretching progressively increases away from the pants cuff. This condition is particularly desirable, as the major degree of stretching is adjacent the knee of the pants where it is most needed. Relatively little stretching is possible at a pants cuff, in any event, and the present device operates on a pants leg where and as needed.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative, and that such changes may be made, when desired, as fall within the scope of the appended claims.

Having thus described my invention, I claim as new and desire to secure by Letters Patent of the United States the following:

1. A pants-leg stretcher of the character described comprising a pair of spaced flat stretcher bars for coplanar disposal within a pants-leg for engagement within the creases

thereof, a strut pivotally connected to the end of one bar, ratchet teeth formed along one edge of the other end of the strut, a pawl extending transversely from the end of the other bar adjacent said ratchet teeth for engagement therewith whereby the bars may be adjustably spaced through the medium of said strut and pawl, angularly related links pivoted to said bar ends and to each other, 10 angularly related toggle links pivoted to said bars at corresponding points thereof and spaced from said bar ends, a pivot pin connecting said toggle links, a pull rod extending from said pivot pin in the plane of said bars for displacing said pin to effect angular adjustment of said bars to an operative engagement with the pants-leg, and means co-active between said pull rod and said strut to releasably secure the rod for retaining the 20 toggle links in fully operative position.

2. A pants-leg stretcher of the character described comprising a pair of spaced flat stretcher bars for coplanar disposal within a pants-leg for engagement within the creases thereof, a strut pivotally connected to the end of one bar, ratchet teeth formed along one edge of the other end of the strut, a pawl extending transversely from the end of the other bar adjacent said ratchet teeth for engagement therewith whereby the bars may be adjustably spaced through the medium of said strut and pawl, angularly related links pivoted to said bar ends and to each other, angularly related toggle links pivoted to said 25 bars at corresponding points thereof and spaced from said bar ends, a pivot pin connecting said toggle links, a pull rod extending from said pivot pin in the plane of said bars for displacing said pin to effect angular adjustment of said bars to an operative engagement with the pants-leg, and means co-active between said pull rod and said strut to releasably secure the rod for retaining the 30 toggle links in fully operative position, said 35 means comprising ratchet teeth formed along one edge of said rod and engageable with said strut.

In testimony whereof, I affix my signature.
MARION F. MITAR.
